G. A. GRAY, Jr.
RADIAL DRILLING MACHINE.

No. 97,908.

Patented Dec. 14, 1869.

Fig. 1.

Fig. 2.

United States Patent Office.

GEORGE A. GRAY, JR., OF CINCINNATI, OHIO.

Letters Patent No. 97,908, dated December 14, 1869.

IMPROVED RADIAL DRILLING-MACHINE.

The Schedule referred to in these Letters Patent and making part of the same.

To all whom it may concern:

Be it known that I, GEORGE A. GRAY, Jr., of Cincinnati, Hamilton county, State of Ohio, have invented certain new and useful Improvements in Radial Drilling-Machines; and I do hereby declare the following to be a sufficiently full, clear, and exact description thereof, to enable one skilled in the art to which my invention appertains, to make and use it, reference being had to the accompanying drawings, making part of this specification.

My invention relates to that class of drilling-machines which has a radially-adjustable arm, in which the drill-spindle is journaled; and consists, first, in a peculiar construction of the column to which the swinging arm is secured, in connection with a peculiar device for attaching the same to the bed-plate of the machine; second, in the formation of the bed-plate, in connection with the devices for firmly securing the column and arm in any required position; third, in an improved and simple device for securing the drilling-table on which the work rests, to the bed-plate of the machine.

In the accompanying drawings—

Figure 1 is a perspective view of a drilling-machine embodying my improvements.

Figure 2 is an axial section of the parts of the machine which embody my improvements, detached from the rest.

A is the bed-plate of the machine; B, the column; and C, the swinging arm, to which the drill-spindle is attached.

The spindle D is journaled in the frame E, which can be adjusted to drill at any angle.

The frame E, and the slide or saddle F, to which it is attached, are designed to be adjusted along the arm C, by means of the screw G, the gearing by which the drill is driven, sliding along the driving-shaft H.

The arm C carries a pair of mitre-gears, I, which slide on a feather up and down their driving-shaft L.

The power is communicated from central driving-shaft J, through gearing K K'.

The arm C is elevated and depressed by power, by means of screw M working through a half nut, N, in the socket c of the arm, a groove being planed in the column B, in which the screw fits and rests.

A gear-wheel, O, is fitted to the screw M, for the purpose of driving the same.

The swinging lever P carries two pinions, geared together, one of which is also geared to the wheel O.

Each of these pinions is arranged to gear with the wheel Q on the shaft J when thrown into gear by lever P, the connection with one serving to run the arm up, and with the other, down. When between the two, the arm C remains at rest.

The arm C has a socket, c, which clamps on the

column, for securing the same at any height to which it may have been adjusted, by means of bolts R. The screw M serves to prevent the arm from turning on the column B. This column, as shown, is cylindrical, in order that it may be easily finished to size, and it is connected to the bed-plate A, on which it swivels, by the following device:

The column is bored out for a considerable distance from the bottom flanch b, and a cylindrical sleeve, S, is closely fitted to the bore, as shown, the sleeve being permanently secured to the bed-plate by bolts T. The lower face of the flanch b is "faced off," to fit accurately against the planed face of the bed-plate A. It will be seen, that by the provision of the sleeve S, the column is preserved in a vertical position against the pressure of the drill, even when not additionally secured, and the column is retained in its position on the bed-plate; and also, that the lower part of the column or base is materially strengthened.

To rigidly secure the column in any required position, I provide the bolts U. The ordinary device for connecting a swivelling part of a machine to a stationary one, is a T-shaped groove in the stationary part, in which the bolt-heads fit and connect. As it is next to impossible to employ this device to connect the column B to the bed-plate A, owing to the difficulty of turning out the T-groove at one end of so large a plate, I have devised the following substitute:

A plain groove, a, is provided in the plate A, for the heads of the bolts U, but the heads do not fit the groove, and the groove is not turned or otherwise "finished."

The flanch s of the sleeve S, is made of such a size as to project over the groove a, as shown, and against the lower face of this flanch, which is, of course, "faced off," the bolts are held. The shanks of the bolts may be square, to prevent turning, and are fitted closely to the flanch s, as shown.

They fit closely in the holes provided for them in the flanch b, and are fitted with tightening-nuts u.

V is the drilling-table. To provide against the necessity of bolt-heads for holding this to the bed, which would project, be in the way, and catch dirt, I have designed the following connection, which is simple, cheap, quite effective, and permits of a smooth, pleasing finish being given to the base of the table.

The column v of the table is cast hollow, as shown, and has a diaphragm or partition, v', cast within it, at a sufficient distance below the top of the table to form a chamber for the reception of chips, clearance of drill, &c.

By means of the large bolt W, which passes through this partition v', the head shouldering against the same, as shown, the table V is connected to the bed-plate A.

I claim herein as new and of my invention,

1. In connection with a radial drilling-machine constructed to operate substantially as described, the cylindrical column $B\ b$, interior sleeve S , and arm C having a spring-socket, e , the whole being arranged substantially in the manner and for the purpose stated.

2. In combination with the column $B\ b$, and bolts and nuts $V\ u$ for securing the same, the groove a , and flange s , constructed as described, and operating substantially as set forth.

3. In combination with the bed-plate A and bolt W , the drilling-table V , constructed as described. In testimony of which invention, I hereunto set my hand.

G. A. GRAY, Jr.
